STAIR CONSTRUCTION

Filed Dec. 29, 1944

UNITED STATES PATENT OFFICE

2,406,497

STAIR CONSTRUCTION

Michael Hurley, Denver, Colo.

Application December 29, 1944, Serial No. 570,268

6 Claims. (Cl. 189—43)

1

This invention relates to a stair construction adapted for prefabrication in the form of units susceptible of convenient interengaging assembly to meet the stair requirements of a given installation, and has as an object to provide an improved such construction.

A further object of the invention is to provide an improved interengageable relation of stringer and step units constituting a stair assembly.

A further object of the invention is to provide an improved construction of cooperating stringer and step units adapted for prefabrication in quantity and subsequent assembly at the site to meet varying stair requirements of specific installations.

A further object of the invention is to provide an improved construction of stair stringer arranged to successively receive, engage with, and support corresponding ends of a plurality of step units constituting a stair flight.

A further object of the invention is to provide an improved stair step unit construction successively engageable in supported relation with a pair of stringers to constitute a stair flight.

With the foregoing and other objects in view, my invention consists in the construction, arrangement, and combination of elements hereinafter set forth, pointed out in my claims, and illustrated by the accompanying drawing, in which—

Figure 1 is a somewhat diagrammatic cross section taken longitudinally through an incomplete stair flight embodying the principles of the invention. Figure 2 is a fragmentary, detail section through a stair flight construction similar to Figure 1 and illustrating a modification of the showing of the latter figure. Figure 3 is a cross section, on an enlarged scale, taken on the indicated line 3—3 of Figure 1. Figure 4 is a view similar to Figure 3, on the same scale as Figure 1, illustrating modifications of construction and arrangement embraced within the inventive concept.

The improved stair construction of the invention includes stringer elements susceptible of convenient prefabrication from standard shapes and sizes of structural units in lengths adjusted to the span and anchorage characteristics of a given flight installation, or in non-adjusted lengths readily workable at the site for adaptation to specific installation requirements, and step units, each embodying a tread and a riser portion, arranged for convenient successive engagement in supported relation with a pair of such stringers to complete the desired stair flight.

The stair-flight-supporting stringers of the invention may be of any material, size, shape, and specific construction suited to their function and cooperative relationship with the step units as hereinafter set forth, it being fundamental to the

2

purposes of the invention that said stringers be designed to carry the loads contemplated to be imposed on the flight which they support and that the stringer construction provide a continuously-uniform interior chamber opening through at least one end of each stringer and lengthwise thereof through a straight, relatively-narrow, longitudinal slot intersecting a stringer wall and opening through the stringer open end. As typically shown in Figures 1, 2, and 3, the stringers of the invention may, for many installations, take the form of straight, tubular members 10, of suitable size, length, and strength, formed with straight, longitudinal slots 11 throughout their lengths, and susceptible of fixed disposition, in any appropriate manner, to bridge the span of the stair flight at the desired inclination; Figure 4 illustrating an alternative or modified form of stringer 10', of box-girder or analogous type susceptible of fabrication as a single rolled section or as an assembly of standard structural shapes, incorporating and characterized by the longitudinal slot 11.

Step units of the improvement, as represented by the drawing, are designated by the numeral 12, and each of said units includes rigidly and perpendicularly interrelated tread and riser portions 13 and 14, respectively, fixedly engaging at their ends with and in perpendicular relation to end webs 15 similarly projecting in spaced, parallelism from the unit ends. The step units 12 may be formed and constructed in any convenient and suitable manner from any appropriate material, the length of the unit tread and riser portions being determined at the time of unit manufacture to provide the desired width of completed stair, and the width of tread 13 and height of riser 14 being also proportioned in manufacture to develop the desired angle or slope in the completed flight. The webs 15 preferably correspond in width with their associated treads 13 and have lengths greater than the heights of their associated risers 14, and are so related to their tread and riser portions as to assume substantially vertical positions when the associated tread is horizontally disposed. Ends of the webs 15 remote from the associated treads 13 are sloped or inclined, as indicated at 16 in Figure 1, to such angle with the plane of the associated tread 13 as the slope of the finished flight is to make with the horizontal, the longer side margin of each web 15 rising from and extending above the associated riser 14 and the shorter web side margin rising from and extending above the free edge of the associated tread 13. Inwardly adjacent and paralleling the sloped margin 16 of each web 15, lugs or ears 17 are provided in suitable fixed, projecting relation with one or both of the web surfaces, said lugs or ears being struck from the material of the webs, as shown, or otherwise formed on or

secured to the web surfaces in any conveniently effective manner to provide a web thickness greater than the width of the slot 11 in the stringer wherewith the step unit is to be associated. The ears or lugs 17 are so disposed and arranged on each web 15 as to define by their emergence with the web plane a line paralleling the sloped end 16 of the web, said line of emergence lying on the side of the lugs or ears 17 remote from the sloped end 16 at a distance from said sloped end corresponding with the depth of the stringer interior chamber, so that, when a web 15 is edgewise engaged in the slot 11 of a stringer 10 or 10' with its sloped end 16 in sliding relation with the unslotted side of said stringer, in the manner indicated at the upper end of Figure 1, the ears or lugs 17 are disposed within the stringer chamber adjacent and in position to bear against inner margins of the slot 11 where they serve to slidably mount the corresponding end of the step unit on the associated stringer and hold said step unit against radial or lateral separation from the stringer.

With the construction and arrangement of elements shown and above described, the stair flight may be completed by suspending the successive step units from and beneath a pair of stringers with their tread portions extending forwardly relative to their associated riser portions, as shown in Figures 1, 2 and 3, or the stringers may be positioned with their slots opening upwardly, the step units reversed, and the flight completed by engaging the said units with and to rise above the stringers in such disposition as places the unit tread portions in rearwardly extending relation with their associated riser portions, as shown in Figure 4.

As is indicated in Figure 2, the completed flight may be arranged to dispose the stringers as handrails, the only variation in construction required being an increase in the length of the step unit webs 15.

The laterally-disposed meeting edges of adjacent step units may be variously worked for such structural cooperation as may be deemed desirable for a given installation, it being essentially unnecessary that said edges interengage other than along a simple line of contact. However, as is indicated in the drawing, said edges may be finished as correspondingly inclined flanges 18 adapted for surface interengagement and such interconnection, as by means of studs, lugs, bolts, rivets, welds, and the like, as may be desired.

The step unit tread, riser, and web portions may be fabricated and finished in either solid or skeleton form to function as exposed elements for the purposes designed, or, as may be more generally the case, said portions may be fabricated and finished to receive, position, and support covering material and elements, wear surfaces, plastic compositions, and the like, in a common and well-known manner.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A stair construction comprising a pair of hollow, longitudinally-slotted stringers, step units formed with end webs extending perpendicularly from the tread portions thereof engageable

through and longitudinally of the slots of said stringers, and lugs outstanding from the stringer-engaging web portion faces cooperable interiorly of and with said stringers to inhibit web displacement laterally and radially thereof.

2. A stair construction comprising a pair of like, hollow stringers each formed with an end-opening, longitudinal slot, step units formed with end webs extending perpendicularly from the tread portions thereof engageable through and longitudinally of the stringer slots in end-abutted, slidable relation with the slot-opposed stringer wall, and lugs outstanding from stringer-housable face portions of said webs disposed for cooperation with interior slot margins to inhibit displacement of said webs laterally and radially of said stringers.

3. In a stair construction, a pair of like, hollow stringers, an end-opening slot longitudinally of each said stringer, and a plurality of like step units formed with end webs extending perpendicularly from the tread portions thereof successively engageable through and longitudinally of said slots in slidably supported relation with said stringers.

4. In a stair construction, a pair of like, hollow stringers, a plurality of like step units, and means for successively engaging said units in slidably supported relation with said stringers, said means comprising an end-opening slot longitudinally of each stringer, end webs on and extending perpendicularly from the tread portions of said step units engageable through and longitudinally of said slots in end-abutted, slidable relation with the slot-opposed stringer wall, and lugs outstanding from the stringer-housable web portion faces disposed for slidable cooperation with interior slot margins.

5. In a stair construction, a pair of like, hollow stringers, a plurality of like step units presenting rigidly and perpendicularly interrelated tread and riser portions, and means for successively engaging said units in slidably supported relation with said stringers to complete a stair flight, said means comprising an end-opening slot longitudinally of each stringer, end webs rigidly associated with and extending perpendicularly from the tread portion of each step unit for engagement through said stringer slots, free end portions on said webs parallel to the slope of the stair flight for slidable, step-positioning engagement against the slot-opposed stringer wall, and lugs outstanding from the stringer-housable web portions disposed in spaced parallelism with the inclination of the web free end for slidable cooperation with interior slot margins.

6. In a stair construction having a pair of like, hollow stringers each formed with an end-opening, longitudinal slot, a plurality of step units successively and slidably engageable in supported relation with said stringers to complete a stair flight, each of said step units comprising, in a rigid unitary assembly, perpendicularly-interrelated tread and riser portions, parallel end webs perpendicularly engaging with said tread and riser portions and extending longitudinally beyond the associated riser, free end portions on said webs parallel to the slope of the stair flight and engageable through the stringer slots, and lugs outstanding from the stringer-housable web end portions disposed in spaced parallelism with the inclination of the web free end for slidable cooperation with interior slot margins.

MICHAEL HURLEY.
